UNITED STATES PATENT OFFICE.

ERNST CURT MÜHLBAUER, OF DRESDEN-LÖBTAU, GERMANY, ASSIGNOR TO UNIVERSAL CIGARETTEN-MASCHINEN-INDUSTRIE SYSTEM OTTO BERGSTRÄSSER AKTIEN-GESELLSCHAFT, OF DRESDEN-LÖBTAU, GERMANY.

MACHINE FOR APPLYING CORK, METAL FOIL, OR THE LIKE AT INTERVALS TO STRIPS OF CIGARETTE-PAPER.

1,259,548.

Specification of Letters Patent. Patented Mar. 19, 1918.

Application filed December 16, 1913. Serial No. 807,023.

To all whom it may concern:

Be it known that I, ERNST CURT MÜHLBAUER, a citizen of the Kingdom of Saxony, German Empire, residing in Dresden-
5 Löbtau, in the Kingdom of Saxony, in said Empire, have invented certain new and useful Improvements in Machines for Applying Cork, Metal Foil, or the like at Intervals to Strips of Cigarette-Paper, of which
10 the following is a specification.

The invention is shown in the accompanying drawing in Figures 1 and 2 in side and front elevation respectively. Fig. 3 is a detailed view showing the knife in its cutting position. Figs. 4, 5 and 6 are detailed views showing the knife 25 and the clamping bar 27 in three positions, namely, before the covering strip is gripped, while the covering strip is gripped and before the cutting 15 thereof, and lastly, after the cutting and releasing of the covering strip. Fig. 7 is a cross section of the feed gear. Fig. 8 is a longitudinal section thereof. Fig. 9 is a top detailed view of the feed for the cigarette 20 paper. Fig. 10 is a top detailed view of the clamping apparatus. Fig. 11 is a detailed view of the balls or rollers in the feed gear. Fig. 12 is a view of a separate piece of the 25 covering strip. Fig. 13 is a detailed top view of the cigarette paper, showing portions thereof covered with paste.

The toothed wheel 1 drives the toothed wheel 2 which is journaled at 3 in the body A of the machine. On the shaft 3 of the 30 toothed wheel is fitted a crank 4 which is coupled by screws 5 and 5' with the wheel 2 and can be displaced relatively thereto, the screw 5 passing through a slot 6. To the crank is coupled a connecting rod 7, which 35 acts by means of a lever 8 on the driven part 9 of a free wheel feed gear shown in detail in Figs. 7, 8, 11. This driven part 9 is surrounded in the manner well-known in cycle free wheels with a shell 10. Between the 40 two parts 9 and 10 are arranged balls or rollers 11, which coact in well-known manner with bevels 12 on the driven part 9, so that when the lever 8 is rocked in the one direction (direction of the arrow in Fig. 1) 45 the balls are gripped by the bevels 12 and the shell 10 is moved correspondingly, while when the lever 8 is rocked in the opposite

direction the balls are released so that only the driven part 9 of the gear is gripped. The space for the balls must, of course be 55 made to correspond with the length of the longest stroke of the lever 8. In order to keep the shell 10 in its position of rest while the gear is running idle pawls 13 are provided, which bear frictionally against the 60 shell 10 of the roller. When, at the reversed rotation the shell of the roller is gripped, the friction of the pawls 13 is overcome. The pawls 13 are pressed against the roller by means of springs 14 and a lever 15. 65

Over the shell 10 of the feed gear, a covering strip B coming from the stock of the reel C is conducted. This strip is made in the manner well known, and consists of the covering material *per se* carried on an auxiliary strip, which serves to transport this covering material. With the shell 10 permanently coacts a roller 16, which is driven by a toothed wheel 18 on the shaft 17 of the feed gear by aid of the toothed wheel 19 70 (Fig. 2). The roller 16 is journaled in a double armed lever 21, which is constantly drawn by a spring 22 into the position, at which the roller 16 coacts with the shell 10 of the feed gear. The front end of the 75 double armed lever 21 is made at the same time so as to act as the upper guide 23 for the covering material, which is intermittently advanced between this part 23 and the table 24 by the coöperation of the roller 16 and the shell 10. 80

Immediately behind the guide slot between the parts 23 and 24 is fitted the blade 25, which coacts with the edge 26 of the table 24, and severs the several pieces of covering 90 from the strip. During such severing the covering strip is held in front of the cutting point, because the rollers 16 and 10 remain stationary during a cut. Behind the cutting point the clamping bar 27 is provided for 95 holding the material, which bar is controlled in the well-known manner with reference to the blade 25 so that when the blade moves down the bar bears on the covering material and holds it tight during the cut. 100

The clamping bar is fitted to a rocking lever 28, which rocks on the pin 29, and is drawn by a spring 30 permanently into the position, at which the clamping bar 27 holds

the material. On the lever 28 is a rearward projection, 31, on which an adjustable screw pin 32 acts, which is fitted to the roller carrier 33. This roller carrier rocks on the 5 fixed pin 34, and carries the roller 35 over which the strip of cigarette paper D is passed. The roller carrier is drawn by a spring 36 in an upward direction and is controlled in its movement by means of a cam 10 disk 37, which coacts with a roller 38 at the end of the roller carrier. The cam disk 37 presses the roller carrier down contrary to the action of the spring 36 at the moment when that part of the paper strip D having 15 an adhesive applied has reached a position opposite to the covering piece which has been cut off. When the roller carrier moves downward, the roller 35 is pressed against the roll 39, which is driven from wheel 1 by 20 means of toothed wheel 40. The cigarette paper is joined with the tip covering and both parts are simultaneously advanced between the rolls 35 and 39. Before this movement commences, the clamping bar 27 25 must, however, be lifted from the tip covering. This is effected by the set pin on the roller carrier 33, which pin presses on the end 31 of lever 28 before the roller bears against the roll 39; as the clamping bar 27 30 is secured to the said lever 28, it is slightly lifted from the severed tip covering.

As is seen from Fig. 1, the movement of the connecting rod 7 caused by the crank 4 can be varied by changing the position 35 of the screw 5 in the slot 6. The screw 5 can be unloosened and the arm connected thereto, placed in any desired portion of the slot 6, and maintained in that position by again tightening the screw 5. In this manner, the connecting rod 7 can be given a 40 movement of regulated length.

I claim:

1. In a machine for applying covering material at spaced intervals to a strip of cigarette paper, a reel, coating rollers having peripheries of uniform curvature between which said strip is led, and means for intermittently revolving said rollers, whereby said strip is intermittently withdrawn from said reel, separate means for severing said strip after it passes away from said rollers, and separate means for feeding said severed strip so as to contact with the cigarette paper at a given portion thereof. 50

55 2. In a machine for applying covering material at spaced intervals to a strip of cigarette paper, a reel, means for withdrawing said strip from said reel, a knife for severing said strip after it has been withdrawn from said reel, a table on which said strip lies during the severing thereof, clamping means for holding said strip on said table during the severing thereof, a free roller over which the cigarette paper is 60 passed, a driven roller, means for placing 65

said free roller in and out of coaction with said driven roller, so as to feed the cigarette paper, and releasing mechanism for releasing said clamping means from said strip, whereby the severed portion of said strip 70 can then be fed intermediate the said free roller and said driven roller to contact with the cigarette paper, and means for operating said releasing mechanism by and during the movement of said free roller toward said 75 driven roller, said releasing mechanism being operated before said free roller comes into cooperative position with respect to said driven roller, so as to be revolved by said driven roller. 80

3. In a machine for applying covering material at spaced intervals to a strip of cigarette paper, a reel, means for withdrawing said strip from said reel, a knife for severing said strip, a table on which said strip lies during the severing thereof, a clamping bar mounted on a pivoted lever, a spring for normally revolving said lever so as to move said clamping bar against said table, and a free roller over which the cigarette paper passes, said free roller being mounted on a pivoted lever, a driven roller, adapted to coact with said free roller to feed the cigarette paper, means for revolving the lever holding said free roller so as to place said free roller in and out of coaction with said driven roller, and a pin carried by said lever holding said free roller, said pin being adapted to contact with the lever holding said clamping bar and revolve 90 it so as to raise said clamping bar from said table, before said free roller contacts with said driven roller. 95

4. In a machine for applying covering material at spaced intervals to a strip of cigarette paper, coating rollers having peripheries of uniform curvature, between which said strip is led, and adapted to withdraw said strip from said reel when they are revolved, a connecting rod, a crank, a 105 driven wheel having a slot therein, means for connecting said crank to said wheel at different portions of said slot, whereby the action of the crank and the movement of the connecting rod can be varied, and connecting means intermediate said connecting rod and one of said rollers, said connecting means locking with said roller and revolving it in a given direction when the connecting rod is moved in one direction, and 110 being unlocked from said roller when the connecting rod is moved in the opposite direction, whereby said roller is intermittently revolved. 115

5. In a machine for applying covering material at spaced intervals to a strip of cigarette paper, the said covering material being in the form of a strip wound up on a reel, coating rollers having peripheries of uniform curvature between which said strip 120

on said reel is led, a crank, a connecting rod connecting one of said rollers to said crank, connecting means intermediate said rollers, whereby the rotation of the said roller connected to the said crank causes the rotation of the other roller, a driven wheel having a slot therein, and a lever connected to said driven wheel by two screws on opposite sides of the center of said driven wheel, one 10 of said screws being adjustably fastened in

the aforesaid slot, the said connecting rod being connected to the said lever.

In testimony that I claim the foregoing as my invention, I have signed my name in presence of two subscribing witnesses.

ERNST CURT MÜHLBAUER.
